CLAIM

The ornamental design for a bottle or other accessories mount, as shown and described.

DESCRIPTION

FIG. 1 is a perspective view of a bottle or other accessories mount showing the new design;

FIG. 2 is a rear elevation view thereof;

FIG. 3 is a front elevation view thereof;

FIG. 4 is a right side elevation view thereof;

FIG. 5 is a left side elevation view thereof;

FIG. 6 is a top view thereof; and,

FIG. 7 is a bottom view thereof.

The broken lines and unshaded surfaces bounded by broken lines form no part of the claimed design.

1 Claim, 6 Drawing Sheets
